COMBINED SPEAKER AND CARRYING CASE FOR TAPE PLAYER AND CASSETTES

Norman E. Savoy, 123 Hampton Ave.,
Brooklyn, N.Y. 11235

Filed Apr. 3, 1974, Ser. No. 457,581

Term of patent 14 years

Int. Cl. D3—02

U.S. Cl. D87—1 R

Fig. 6.

Fig. 1.

Fig. 2.

Fig. 3.

Fig. 4.

Fig. 5.

FIG. 1 is a front perspective view of a combined speaker and carrying case for tape player and cassettes showing my new design in open position;

FIG. 2 is a top plan view thereof;

FIG. 3 is a front elevational view thereof;

FIG. 4 is a front elevational view of the combined speaker and carrying case for tape player and cassettes in a closed position;

FIG. 5 is a side elevational view thereof; and

FIG. 6 is a top plan view on a reduced scale, the bottom plan view being similar.

I claim:

The ornamental design for a combined speaker and carrying case for tape player and cassettes, as shown and described.
